A. H. Cottingham,

UNITED STATES PATENT OFFICE.

ARTHUR H. COTTINGHAM, OF UNION, SOUTH CAROLINA.

BOBBIN-STRIPPER.

1,270,703.

Specification of Letters Patent. Patented June 25, 1918.

Application filed September 24, 1917. Serial No. 192,992.

To all whom it may concern:

Be it known that I, ARTHUR H. COTTINGHAM, a citizen of the United States, residing at Union, in the county of Union and State 5 of South Carolina, have invented certain new and useful Improvements in Bobbin-Strippers; and I do hereby declare the following to be a full, clear, and exact description of the invention, such as will enable others skilled in the art to which it app- 10 pertains to make and use the same.

The present invention relates to improvements in bobbin strippers, and has for one object to produce an improved machine for 15 quickly and effectively removing the residue of the roving from the bobbin after the bobbin has become practically exhausted and is removed from the spinning frame.

The improved stripper will be more fully 20 described in connection with the accompanying drawings, in which:

Figure 1 is a rear elevational view of an 25 improved bobbin stripper constructed in accordance with the present invention; and

Fig. 2 is a vertical sectional view taken on the line 2—2 of Fig. 1.

Referring more particularly to the drawings, 1 and 2 designate end pieces of a framework, which are connected together by beams 30 3 and 4 and a rod 5.

Supported in any suitable manner in this framework is a casing 6, having its upper end opened as indicated at 7, and containing a pair of superposed stripper rolls 8 and 9 35 revolving on shafts 10 and 11, respectively. These shafts pass through the end walls of the casing 6 and are journaled in the end pieces 1 and 2 of the framework.

The rolls or cylinders 8 and 9 are each 40 covered with a stripper fillet 12 and 13 which is preferably of fine wire, and the upper roll 8 is exposed through the opening 7 of the casing, so that an operator may place the bobbins thereon in the manner shown at 14 45 in Fig. 2. These bobbins 14 are held in this position by the hand of the operator until the bobbin has been completely cleaned.

The casing 6 has the back wall thereof extended to form a flange 15, which provides 50 an abutment against which the bobbin may rest if desired, and which catches the bobbin if same escapes the hand of the operator, preventing such bobbin from entering the casing 6.

55 The bobbins are contained in a trough 16 held upon a bracket 17 secured in any de-

sired manner to the framework, and there is preferably an apron 18 constituting part of the casing 6, being bent over therefrom and engaging with an upper edge of the trough 60 16 in the manner best illustrated in Fig. 2.

The upper shaft 10 is provided with a pulley 19, while the lower shaft is furnished with a pulley 20 of smaller diameter, whereby to drive the lower stripper roll 9 at an 65 increased speed over that of the upper stripper roll 8.

An open belt 21 connects the pulley 19 with a pulley 22 on a drive shaft 23; and a crossed belt 24 similarly connects the pulley 70 20 to a pulley 25, also on the drive shaft 23. A power belt 26 provides for driving this shaft 23 and engages with fast and loose pulleys 27 and 28; it being moved to be engaged by a belt shifter 29. 75

On the drive shaft 23 is also a fan or other suction producing device 30, communicating with the lower end of the casing 6 by a pipe 31, and serving to draw air from the atmosphere into the opening 7 and past the stripper rolls 8 and 9, for the purpose of removing the roving, which has been stripped from the bobbins, therefrom. After being withdrawn from the casing 6 by the fan 30, this roving is delivered to a suitable receptacle 80 85 through a pipe 32.

In use the power belt 26 is shifted to the fast pulley 28, which thereupon puts the drive shaft 23 in motion. The drive shaft 23 in turn, through the belts 21 and 24, communicates a rotary movement to the shafts 10 and 11, such movement being in opposite directions and resulting in driving the lower shaft 11, and its stripper roll 9, at an increased speed over that of the upper shaft 10 90 and its stripper roll 8. The fillet 13 on the lower stripper roll 9, by reason of its contact with the fillet 12 on the upper roll 8, will having a combing effect on the upper fillet 12, such as will serve to keep same clean; this 100 effect being enhanced by the difference in direction and speed at which these rolls are driven.

The operator places one or two bobbins in the position shown at 14 in Fig. 2, where 105 he manually holds same. The stripper fillet 12 of the upper roll rotates in contact with the roving on the bobbin and pulls such roving apart and from the bobbin, carrying the stripped roving down into the casing 6, 110 where it will come under the influence of the suction produced by the fan 30 and is

withdrawn therefrom and delivered by the pipe 32 to a suitable receptacle.

Adjustable bearings are preferably provided for the trunnions of the shaft 10, 5 which may be operated by screws 33 in order to raise and lower the upper roll 8, with respect to the lower roll 7. Gage-bars 34 and 35 are also advantageously mounted above the top roll 8, they being shaped approximately after the manner shown in Fig. 2, 10 and adapted to receive the bobbin 14 in such a way as to prevent the operator from mashing the bobbins down into the clothing 12 of said roll 8. These gage-bars may be made 15 to assume any desired position by adjustable set screws 36, and when properly set they should hold the bobbin so that the roving thereon will barely come in contact with the clothing, as it is found that this method 20 of operation is productive of the best results.

It is obvious that those skilled in the art may vary the details of construction and arrangement of parts without departing from 25 the spirit of my invention, and therefore I do not wish to be limited to such features except as may be required by the claims.

I claim—

1. A device of the character described including bobbin stripping means having a 30 stripping fillet thereon, means for actuating said bobbin stripping means, gage-bars for receiving the ends of the bobbin and permitting the roving on the intermediate portion 35 of the bobbin to be brought into contact with the stripping fillet, and means to adjust said gage-bars whereby to regulate the position of the bobbin to and from said stripping fillet, substantially as described.

40 2. A device of the character described including bobbin stripping means having a stripping fillet thereon, means for actuating said bobbin stripping means, a gage-bar constructed to receive and form a stop for one 45 end of the bobbin, and a second gage-bar spaced from said first named gage-bar and constructed with a supporting surface for receiving the other end of the bobbin so that the intermediate part with the roving there- 50 on will extend in contact with the stripping fillet, substantially as described.

3. In a device of the character described, the combination of a bobbin stripping means, 55 means for actuating said bobbin stripping means, a gage-bar constructed to receive and form a stop for one end of a bobbin, means to adjust said gage-bar to and from said stripping means, a second gage-bar having a supporting surface for the other end of the 60 bobbin whereby to hold the bobbin extending in contact with the stripper fillet, means

for adjusting said second named gage-bar to and from said stripping means, and means for carrying off the roving after it has been removed from the bobbin by said stripping 65 means, substantially as described.

4. In a device of the character described, the combination of a rotating bobbin stripping roll, a cleaning roll rotating in contact with said bobbin stripping roll, means for 70 adjusting said bobbin stripping roll toward and away from said cleaning roll, gage-bars for receiving the ends of a bobbin to hold the intermediate part thereof with the roving thereon in contact with said stripping roll, and means for adjusting said gage-bars to and from said stripping roll, substantially as described.

5. In a device of the character described, the combination of a casing having an open 75 upper end, a stripping roll rotating in said casing and exposed through the upper end thereof, a cleaning roll, means for driving said cleaning roll at a higher speed and in a direction opposite to the rotation of said 80 stripping roll, gage-bars for receiving the ends of a bobbin and holding the intermediate part thereof with the roving thereon in contact with said stripping roll, adjustable 85 means for shifting said gage-bars with respect to said stripping roll, and suction producing means connected to said casing for removing the stripped roving, substantially 90 as described.

6. In a device of the character described, 95 the combination of a framework, a casing supported in said framework and having an open upper end, a stripping roll rotating in said casing, a shaft journaled in said framework for supporting said stripping 100 roll, a cleaning roll rotating in said casing in contact with said stripping roll, a shaft journaled in said framework and supporting said cleaning roll, means for adjusting said stripping roll shaft to move the stripping roll toward or away from said cleaning roll, means for driving said stripping roll, means for driving said cleaning roll at a speed higher than and in a direction opposite to the direction of rotation of said 105 cleaning roll, suction-producing means connected to said casing for creating a draft therethrough to draw off the stripped material, gage-bars extending across the opening 110 in said casing and adapted to receive the ends of the bobbin to hold the same in contact with said stripping roll, and means for adjusting said gage-bars to and from said stripping roll, substantially as described.

In testimony whereof, I affix my signature. 120

ARTHUR H. COTTINGHAM.
